SELF-PROPELLED COMBINE

Theodore H. Koeber, Barrington, and Robert A. Skyer,
Chicago, Ill., and Donald A. McCallum, Burlington,
Ontario, Canada, assignors to International Harvester
Company, Chicago, Ill., a corporation of Delaware

Filed Feb. 13, 1967, Ser. No. 5,780

Term of patent 14 years

(Cl. D40—1)

Fig. 1.

Fig. 2.

FIGURE 1 is a perspective view taken from the right side of the self-propelled combine showing our new design;

FIGURE 2 is a perspective view taken from the right-rear of the self-propelled combine;

FIGURE 3 is a perspective view taken from the left side of the self-propelled combine with portions of the grain outlet spout fragmentarily shown in broken lines for purposes of illustration only;

FIGURE 4 is a perspective view taken from the right-front of the self-propelled combine; and

FIGURE 5 is a perspective view taken from the left-rear of the self-propelled combine.

The dominant features of our design reside in the proportions shown in full line.

We claim:

The ornamental design for a self-propelled combine, substantially as shown and described.
